Specification for Design.

Patented Jan. 18, 1916.

Application filed May 8, 1915. Serial No. 26,917. Term of patent 3½ years.

To all whom it may concern:

Be it known that I, FREDERICK M. SPENCER, a citizen of the United States, residing at Meriden, county of New Haven, State of Connecticut, have invented a certain new, original, and ornamental Design for Handles for Knives, Forks, and Similar Articles, of which the following is a full, clear, and exact description, reference being had to the accompanying drawings, forming part thereof.

Figure 1; is a side view showing the handle attached to a knife blade and in dotted lines a fork. Fig. 2; is a plan view of the same. Fig. 3; is a cross section of the handle at its largest part.

I claim:

The ornamental design for a handle for knives, forks and similar articles as shown.

FREDERICK M. SPENCER.
